[57] CLAIM

The ornamental design for a lacrosse stick head, as shown.

DESCRIPTION

FIG. 1 is a front elevational view of the lacrosse stick head showing our new design;

FIG. 2 is a plan view thereof;

FIG. 3 is a bottom view thereof;

FIG. 4 is a right side view thereof;

FIG. 5 is a left side view thereof;

FIG. 6 is a horizontal sectional view, taken on the line 6—6 of FIG. 1;

FIG. 7 is a horizontal sectional view, taken on the line 7—7 of FIG. 1; and

FIG. 8 is a fragmentary vertical sectional view, taken on the line 8—8 of FIG. 1.
